UNITED STATES PATENT OFFICE.

RUBY T. BREWSTER, OF NEW YORK, N. Y.

DESIGN FOR A BOX OR SIMILAR CONTAINER.

Application filed March 18, 1927. Serial No. 21,187. Term of patent 3½ years.

To all whom it may concern:

Be it known that I, RUBY T. BREWSTER, a citizen of the United States, residing at New York city, in the county and State of New York, have invented a new, original, and ornamental Design for a Box or Similar Container, of which the following is a specification, reference being had to the accompanying drawing, forming part thereof.

Fig. 1 is a side view of a box or similar container, showing my new design.

Fig. 2 is another side view of a box or similar container.

Fig. 3 is another side view of a box or similar container.

Fig. 4 is another side view of a box or similar container.

I claim:

The ornamental design for a box or similar container, as shown.
